The ornamental design for a clip for holding a removable
golf ball marker, as shown and described.

DESCRIPTION

(22) Filed: **Nov. 17, 2003**

FIG. 1 is a front elevational view of the clip for holding a
removable golf ball marker according to our new design.

FIG. 2 is an elevational rear view thereof.

FIG. 3 is a right side elevational view thereof, the left side
view being a mirror image thereof.

FIG. 4 is a top plan view thereof.

FIG. 5 is a bottom plan view thereof.

FIG. 6 is another front elevational view thereof, showing
in dotted line a disk-shaped ball marker removably secured
to the clip. The disk-shaped ball marker does not form part
of the invention.

FIG. 7 is a top plan view showing in dotted line the position
of the disk-shaped ball marker of FIG. 6; and,

FIG. 8 is a bottom plan view showing in dotted line the
position of the disk-shaped ball marker of FIG. 6.
